CLAIM

The ornamental design for a sideboard, as shown and described.

DESCRIPTION

FIG. 1 is a front-side perspective view of a sideboard showing our new design;

FIG. 2 is a side elevational view thereof;

FIG. 3 is a front elevational view thereof;

FIG. 4 is an enlarged partial perspective view thereof; and,
FIG. 5 is a top view thereof.

The bottom and rear elevation views of the design are not shown and would not depict any aspects of the invention not already shown in the Figures.
